Primary Examiner — Catherine Tuttle(74) *Attorney, Agent, or Firm* — Michael A. Olshavsky(57) **CLAIM**

We claim the ornamental design for a bottle, as shown and described.

DESCRIPTION

FIG. 1 is a front perspective view showing our new design for a bottle;

FIG. 2 is a front elevational view thereof;

FIG. 3 is a rear elevational view thereof;

FIG. 4 is a left side elevational view thereof;

FIG. 5 is a right side elevational view thereof; and

FIG. 6 is a top plan view thereof

FIG. 7 is a front perspective view showing an alternate embodiment of our new design for a bottle;

FIG. 8 is a front elevational view thereof;

FIG. 9 is a rear elevational view thereof;

FIG. 10 is a left side elevational view thereof;

FIG. 11 is a right side elevational view thereof; and,

FIG. 12 is a top plan view thereof.

The broken lines are included for the purpose of illustrating the portions of the bottle that form no part of the claim to the embodiment in which they are shown.
